US0D1099857S

(12) **United States Design Patent** (10) **Patent No.:** **US D1,099,857 S**
(45) **Date of Patent:** **** Oct. 28, 2025**

(54) **PHOTODIODE**

(71) Applicant: **Taiwan-Asia Semiconductor Corporation**, Hsinchu (TW)

(72) Inventor: **Chun-Chieh Lin**, Hsinchu (TW)

(73) Assignee: **TAIWAN-ASIA SEMICONDUCTOR CORPORATION**, Hsinchu (TW)

(**) Term: **15 Years**

(21) Appl. No.: **29/941,003**

(22) Filed: **May 7, 2024**

(57) **CLAIM**

The ornamental design for a photodiode as shown and described.

DESCRIPTION

FIG. 1 is a perspective view of a photodiode showing my new design;

FIG. 2 is front elevational view thereof;

FIG. 3 is a rear elevational view thereof;

FIG. 4 is a left side elevational view thereof, a right side elevational view being a mirror image; and,

FIG. 5 is a top plan view thereof, a bottom plan view being a mirror image.

The broken lines are directed to environment and are for illustrative purpose only and form no part of the claimed design.
